CLAIM

The ornamental design for a LED makeup mirror, as shown and described.

DESCRIPTION

FIG. 1 is a perspective view showing an open position of use of a LED makeup mirror showing my new design;

FIG. 2 is a rear elevational view showing an open position of use thereof;

FIG. 3 is a perspective view thereof, shown in an alternate position;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof; and,

FIG. 9 is a bottom plan view thereof.

The broken lines in the drawing depict portions of the LED makeup mirror that form no part of the claimed design.

1 Claim, 9 Drawing Sheets
